(57) **CLAIM**

The ornamental design for an insulating sleeve for a beverage container, as shown and described.

DESCRIPTION

FIG. 1 is a front elevation view of a first illustrated embodiment of an insulating sleeve for a beverage container showing our new design;

FIG. 2 is a rear elevation view thereof;

FIG. 3 is a right side elevation view thereof;

FIG. 4 is a left side elevation view thereof;

FIG. 5 is a top plan view thereof; and,

FIG. 6 is a bottom plan view thereof.

In the drawings the long dash broken lines in the drawings depict environmental subject matter that forms no part of the claimed design; the short dash lines depict portions of the article that form no part of the claimed design.

1 Claim, 3 Drawing Sheets
